(57) **CLAIM**

The ornamental design for a claw prong bracelet, as shown and described.

DESCRIPTION

FIG. 1 is a front side perspective view of a claw prong bracelet showing our new design;

FIG. 2 is a top plan view of FIG. 1.

FIG. 3 is front elevation view of FIG. 1.

FIG. 4 is a bottom plan view of FIG. 1.

FIG. 5 is a left side elevation view of FIG. 1.

FIG. 6 is a right side elevation view of FIG. 1.

FIG. 7 is a rear side perspective view of FIG. 1; and,

FIG. 8 is a bottom side perspective view of FIG. 1.

The broken lines shown in the drawings illustrate environmental structure that forms no part of the claimed design.

1 Claim, 8 Drawing Sheets
